Primary Examiner — Robert M Spear*Assistant Examiner* — Eliza Bennett-Hattan(74) *Attorney, Agent, or Firm* — Malloy & Malloy, P.L.(57) **CLAIM**

The ornamental design for eyeglasses, as shown and described.

DESCRIPTION

FIG. 1 is a front view illustrating our design for eyeglasses;
FIG. 2 is a top plan view thereof;
FIG. 3 is a left side view thereof; the right side being a mirror image thereof;
FIG. 4 is a front perspective view thereof;
FIG. 5 is a rear view thereof; and,
FIG. 6 is a bottom view thereof.

1 Claim, 6 Drawing Sheets(56)
